J. H. JOHNSON
ELECTROMAGNETIC ACTUATOR

2,548,894

Filed Nov. 16, 1949

UNITED STATES PATENT OFFICE

2,548,894

ELECTROMAGNETIC ACTUATOR

James H. Johnson, Minneapolis, Minn., assignor
to Minneapolis-Honeywell Regulator Company,
Minneapolis, Minn., a corporation of Delaware

Application November 16, 1949, Serial No. 127,610

3 Claims. (Cl. 175—338)

1

This invention relates to electromagnetic actuators of the pivoted armature and movable plunger type and more particularly to means for elimination of noise of engagement and rebound of an armature for such actuators.

The copending application of Willis H. Gille, Serial No. 127,607, filed November 16, 1949, is directed to a stop member or structure for electromagnetic actuators to eliminate noise of engagement and rebound of the armature. The present invention relates to an improvement in actuators of the type disclosed therein.

It is an object of this invention to provide in an electromagnetic actuator of this type a core structure having a flexibly mounted core or stop member so positioned that a predetermined air gap between the core and remaining magnetic structure is maintained upon operation of the electromagnet.

Another object of this invention is to provide a simplified mounting for a movable core member.

Still another object of this invention is to provide in an actuator of this type a core structure in which uniform attraction is attained between parts thereof during operation and the residual magnetism between the parts is substantially prohibited.

These and other objects of this invention will become apparent from a reading of the attached description together with the drawings in which:

Figure 1 is a plan view of the electromagnet utilizing this invention,

Figure 2 is a section of the plan view in Figure 1 to show relationship of parts,

Figure 3 is a side elevation view in section of one embodiment of this invention,

Figure 4 is a bottom view of the mounting structure for the core member of the electromagnet of Figure 2, and

Figure 5 is a sectional view of another embodiment of this invention.

My improved electromagnet is shown in the drawings in the form of a clapper-type electromagnet or relay having a magnetic core structure which includes a stationary core member 10 generally L-shaped in form having a main or base portion 11 with a plurality of upstanding portions 12, 13 are separated into a centrally located portion 12 upon which an armature 15 is adapted to be pivoted and a pair of side portions 13 which serve as backstops for the armature in a manner later to be described. Magnetic core structure 10 including the main portion 11 and upstanding portions 12 and 13 as well as armature 15 are

2

made of a magnetic material of relatively good permeability, such as soft iron, to provide a continuous magnetic circuit.

Armature 15 is generally bar-shaped in form and has attached thereto at its pivoted extremity a brass mounting plate 16 which is secured to the armature 15 through rivets 17 and a reinforcing plate 18, all pieces being made of a non-magnetic material. As shown in Figures 1 and 2, the non-magnetic mounting plate 16 has a pair of notches 20 therein and a centrally located aperture 21 the purposes of which will become evident as the disclosure proceeds. Notches 20 of plate 16 receive projecting guide members 22 of a mounting plate 23 which is attached to upstanding portion 12 of core member 10. Mounting plate 23 is attached to upstanding portion 12 by any suitable means, such as by rivets, and may be made of any material such as iron or brass. With the exception of the guide pins 22, plate 23 is so positioned on the upstanding member 12 that it terminates below the upper edge of the upstanding portion 12 so as not to be in contact with the armature 15. The projecting guides 22 are disposed to one or the other side of the main body of the armature 15 and fit into the slots 20 in the brass mounting plate 16 to guide the armature in its pivotal movement. The upstanding portion 12 of the core structure 10 is beveled as at 25 and engages the armature 15 in a knife-edge engagement. As previously noted brass mounting plate 16 has a centrally located notch on aperture 21 so provided that the upstanding portion 12 of core structure 10 can directly engage the armature 15 to provide a continuous magnetic circuit at this point.

The lower extremity of mounting plate 23 has a transversely extending flange 26 designed to receive and anchor one end of a spring 27, the opposite extremity of which is anchored in a notch or aperture 28 in the extremity of armature 15. In this manner the armature 15 is biased to an open position or biased for counter-clockwise movement about the pivot formed between the upstanding portion 12 and the armature 15. Side sections 13 of the core structure project up to substantially the same level as the centrally located upstanding portion 12 and are spaced to receive the extremity of the armature to provide a backstop therefor. Further, these portions of the core structure provide a parallel magnetic circuit for the core structure which is continuous or without an air gap when the armature is in an open or deenergized position.

Armature 15 at its free extremity carries a

plunger 30 made of a plurality of laminations of magnetic material and attached to the armature proper by means of rivets 31. Plunger 30 extends transversely of the main body of armature 15 and is partially disposed within the confines of a coil 33 mounted on an insulating bobbin 34 and secured to the main body portion 11 of core structure 10. Coil 33 is mounted on the main portion 11 of core structure 10 by means of a brass sleeve 35 which extends through an aperture 36 in the portion 11 of core structure 10, the sleeve being turned or crimped over at its extremities to securely mount the coil to the core structure 10 and align the coil with the aperture 36 and armature plunger 30.

Within the aperture 36 formed in the main portion 11 of core structure 10 is positioned a core member 40 of magnetic material, the core member being generally square in cross section and designed to align with and fit in the aperture 36. Core member 40 has a flanged portion 41 at its lower extremity of the same general thickness as the L-shaped core member 11 and disposed to align with the core member 11 in the same plane. Flanges 41 and the mounting sleeve 35 of coil 33 define an air gap which is very small in comparison to the normal air gap between the core member and plunger 30 when the relay is in an opened position, the former being kept at a minimum allowing only for clearance between the core 40 and spacer member 35. As will be later noted this minimum air gap will always be present in the magnetic circuit, being maintained despite movement of the core under impact of the plunger 30 to prohibit the build-up of residual magnetism in the magnetic circuit.

At the upper extremity of stop member 40 is located a short circuited winding or shading coil 43. The lower extremity of core member 40 is attached by means of spring members 45 to core member 11 to position the core member within the air gap 30 and locate the core member 40 with respect to core member 11. The springs 45 are attached by suitable means, such as riveting, at their free extremities to the core member 11, as at 46. A pair of springs 45, as can be seen in Figures 2 and 3, are mounted so as to be normal to one another and are attached to the core member 40 at their mid-points by means of a screw 47. A spacer member 48 is positioned within the springs and the core member for spacing purposes. In assembled relationship, the core member 40 is aligned in the aperture 36 and due to the flexibility of springs 45 is movable relative to the core member 11 upon impact with the plunger 30 of armature 15 being biased to a normal position in which the flanges 41 are aligned with the main portion of the core structure. As the core member moves up and down with respect to the core structure, the minimum air gap 41 is maintained.

In operation, the magnetic circuit of this actuator defined by the core structure 10 including the main portion 11 and the upstanding portions 12 and 13, the armature 15, plunger 30, the core member 40, and the flanges 41 is energized by the magnetic flux set up with the energization of the winding 33. Such energization of the magnetic circuit provides magnetic attraction between the core member 40 and the plunger 30 such that the plunger and armature will be drawn into the confines of coil 30 in the operation of the actuator. As the main air gap of the magnetic circuit, defined by the spacing between the plunger 30 and core member 40, is decreased,

the attraction between these members is increased and the momentum of the armature is consequently increased. Upon engagement of the plunger 30 with core member 40, the core member moves relative to the remaining portion of the magnetic core structure to absorb the momentum of the armature and noise of engagement. With the plunger 30 and core member 40 in contact with one another substantially maximum attraction between the members will be maintained since the air gaps 41 are kept at a minimum and are not varied with this movement of impact. Upon deenergization of the coil 33, the armature 15 and plunger 30 will return to their normal position under the influence of spring 23. Due to the air gaps 41 which are continuously in the magnetic circuit, a build up of residual magnetism will be prohibited and stickiness of the armature to the core member 40 will be prevented.

Figure 5 of the drawings shows another embodiment of this invention in which the core member 40 is mounted on the main portion 11 of core structure 10 by means of a flexible mounting plate 50 made of a rubber or any other suitable insulating and resiliently yieldable material. The mounting plate 50 is similarly attached to the core member 40 by means of a screw 51 threaded through a washer or reinforcing member 52, and is attached to the core member 11 by any other suitable means such as rivets 53. The operation of this embodiment is the same as that described in connection with Figures 1, 2 and 3, the rubber serving to mount the core member 40 with respect to the core structure such that the momentum of the plunger 30 is absorbed by relative movement between the core member 40 and the remaining portion of the core structure and the noise of engagement is deadened. This mounting through the rubber mounting block 50 also provides for the continued maintenance of the air gaps 41 such that residual magnetism in the magnetic circuit is prohibited.

While the present invention is disclosed in connection with a pivoted armature type electromagnet and is highly advantageous in this type of electromagnetic, it is to be understood that this disclosure is illustratively only and the scope of the invention should be determined by the appended claims.

I claim as my invention:

1. In an electromagnetic actuator, a magnetic core structure including a frame member of magnetic material having an upstanding portion and a transversely extending portion with said transversely extending portion having an aperture therein, a hollow energizing coil for energizing said core structure, a non-magnetic sleeve member extending into said aperture in said transversely extending portion of said frame member being surrounded by said coil and securing said coil on said frame member in alignment with said aperture, armature means including a plate of magnetic material pivotally mounted on said upstanding portion of said frame member and having a plunger attached to the free extremity thereof extending normally thereto and into the confines of said hollow coil, said armature being mounted for pivotal movement about said upstanding portion such that said plunger moves within said coil and out of contact therewith upon energization of said coil and a flow of magnetic flux in said core structure, a magnetic stop member positioned in said

aperture of said transversely extending portion of said frame member and being surrounded by said magnetic sleeve to provide a uniform and minimum air gap therebetween, and flexure mounting means attached and its extremities to said transversely extending portion of said frame member and at its center to said stop member to secure said stop member to said frame member, said stop member being adapted to be engaged by said plunger of said armature means upon energization of said coil and movement of said plunger, said flexure mounting means permitting movement of said stop member to absorb the impact of engagement between said plunger and said stop member maintaining said minimum air gap and flux flow between said members.

2. In an electromagnetic actuator, a magnetic core structure including a frame member of magnetic material having an upstanding portion and a transversely extending portion with said transversely extending portion having an aperture therein, a hollow energizing coil for energizing said coil structure, a non-magnetic sleeve member extending into said aperture in said transversely extending portion of said frame member being surrounded by said coil and securing said coil on said frame member in alignment with said aperture, armature means including a plate of magnetic material pivotally mounted on said upstanding portion of said frame member and having a plunger attached to the free extremity thereof extending normally thereto and into the confines of said hollow coil, said armature being mounted for pivotal movement about said upstanding portion such that said plunger moves within said coil and out of contact therewith upon energization of said coil and a flow of magnetic flux in said core structure, a magnetic stop member positioned in said aperture of said transversely extending portion of said frame member and being surrounded by said magnetic sleeve to provide a uniform and minimum air gap therebetween, and mounting means including a plate of rubber material attached its extremities to said transversely extending portion of said frame member and at its center to said stop member to secure to said stop member to said frame member, said stop member being adapted to be engaged by said plunger of said armature means upon energization of said coil and movement of said plunger, said mounting means permitting movement of said stop member to absorb the impact of engagement between said plunger and said stop member maintaining said minimum air gap and flux flow between said members.

3. In an electromagnetic actuator, a magnetic core structure including a frame member of

magnetic material having an upstanding portion and a transversely extending portion with said transversely extending portion having an aperture therein, a hollow energizing coil for energizing said core structure, a non-magnetic sleeve member extending into said aperture in said transversely extending portion of said frame member being surrounded by said coil and securing said coil on said frame member in alignment with said aperture, armature means including a plate of magnetic material pivotally mounted on said upstanding portion of said frame member and having a plunger attached to the free extremity thereof extending normally thereto and into the confines of said hollow coil, said armature being mounted for pivotal movement about said upstanding portion such that said plunger moves within said coil and out of contact therewith upon energization of said coil and a flow of magnetic flux in said coil structure, a magnetic stop member positioned in said aperture of said transversely extending portion of said frame member and being surrounded by said magnetic sleeve to provide a uniform and minimum air gap therebetween, and mounting means including a plurality of spring members attached at their extremities to said transversely extending portion of said frame member and at their centers to said stop member to secure to said stop member to said frame member, said stop member being adapted to be engaged by said plunger of said armature means upon energization of said coil and movement of said coil and movement of said plunger, said mounting means permitting movement of said stop member to absorb the impact of engagement between said plunger and said stop member maintaining said minimum air gap and flux flow between said members.
